US0D1081373S

(12) **United States Design Patent** (10) Patent No.: **US D1,081,373 S**
(45) Date of Patent: ** Jul. 1, 2025

(54) **WATER BOTTLE**

(71) Applicant: **Shenzhen ZeroOne Premium Network Technology Co., Ltd.**, Guangdong (CN)

(72) Inventors: **Siqi Chen**, Guangdong (CN); **Yurong Lin**, Guangdong (CN)

(73) Assignee: **Shenzhen ZeroOne Premium Network Technology Co., Ltd.**, Guangdong (CN)

(**) Term: **15 Years**

(21) Appl. No.: **29/994,359**

(22) Filed: **Mar. 20, 2025**

(51) LOC (15) Cl. **07-01**

(52) U.S. Cl.
